UNITED STATES PATENT OFFICE.

GEORGE W. HOOS AND RALPH B. STANFORD, OF BALTIMORE, MARYLAND, ASSIGNEES
TO GEORGE W. HOOS, TRUSTEE, OF BALTIMORE, MARYLAND.

SAFETY-RAZOR-BLADE STROPPER.

Application filed July 10, 1926, Serial No. 121,565. Renewed September 20, 1928.

The object of our invention is simplifying the construction of stroppers of well-known type as hereinafter set forth, having our improvements embodied therein.

5 A further object of our invention is providing an improved gripping device preferably integral with the primary driving means of a stropper.

10 A further object of our invention is the providing of improved means for connecting the primary driving means to the driven parts of a stropper.

15 A further object of our invention is an improved power operating means.

20 A further object of our invention is an improved means for maintaining in position the various parts of the stropper.

A further object of our invention is the providing an improved means of assembly 25 of the various parts of a stropper.

A further object of our invention is the providing of an improved means for holding the blades in a stropper.

25 A further object of our invention is an improved means for indicating the position of the blade for extraction.

A further object of our invention is the providing of improved means for securing the operative driven parts within the casing.

30 A further object of our invention is an improved means for forming or securing the various parts of a stropper together.

A further object of our invention is the providing an improved case and means of construction.

35 With the foregoing and other objects in view, our invention consists of the novel construction, combination and arrangement of parts as hereinafter specifically described 40 and illustrated in the accompanying drawing, wherein is shown the preferred embodiment of our invention, but it is understood that changes, variations and modifications may be resorted to which come within the scope of the claims hereunto appended.

45 In the drawings of the herein-described embodiment of our invention, Figure 1 is a plan view, partly in section, of our improved stropper; Fig. 2 is a side view in elevation, partly in section, of the same; Fig. 3 is a sectional view taken on line 3—3 of Fig. 1; Fig. 4 is an end view in elevation, looking in the direction of the arrow shown in Fig. 1; Fig. 5 is a plan view of the spiral driving cam 14 and handle 15; Fig. 6 is an end view

in elevation of the part shown in Fig. 5, looking in the direction of the arrows; Fig. 7 is a plan view of the bridge 17, Fig. 8 being a side view in elevation of the same; Fig. 9 is a plan view of the shuttle washer 13, Fig. 10 being a side view in elevation of the same; Fig. 11 is a plan view of the roller tube 9, Fig. 12 being an end view in elevation of the same; Fig. 13 is a plan view of the blank from which the roller tube 9 is formed; Fig. 14 is a plan view of the blade-holder 21, Fig. 15 being a side view in elevation of the same; Fig. 16 is a plan view of the blank from which the blade-holder 21 is formed, and Fig. 17 is an end view in elevation of the blade-holder.

Similar numerals refer to similar parts throughout the several views.

1 is the casing body, preferably stamped out of sheet metal from the flat and formed in such shapes as shown in Fig. 1, Fig. 2, and Fig. 3, the edges being joined together as shown at 2 in said figures by staggered intermeshing projections. 3 is the head of the operating end of the casing. 4 is the head of the blade insertion end of the casing. Heads 3 and 4 are secured to body 1 by locking projections 5 on body 1 locking over depressed portions 6 in said heads. 7 is the prepared surface of the strop, which may be of leather or any other material suitable for such a purpose. This surface of the strop is mounted to form a roll, preferably on a wooden body 8, by means of glue or otherwise. We have found that occasionally tacking or other securing means is desirable. The wooden body 8 is mounted on roller tube 9 and secured thereon by any well-known means. We have found that a neat fit and the securing tacks 10 a little long which causes them to burr against the side of the roller tube 9 is sufficient to secure the same.

40 In roller tubes 9 are slots 11 through which the projections 12 of the shuttle washer 13 project; these slots in the apparatus shown in the drawing are two in number, one not extending to the end of the tube 9 and the one opposite extending to the end of the tube 9. This feature permits of the introduction of shuttle washer 13 on to roller tube 9 with its projections 12 in said slots 11 without bending or springing either of said parts. 45 14 is the spiral driving cam, in the drawings shown as two in number, formed integral with handle 15 preferably from flat stock.

These cams operate within roller tube 9 and drive shuttle washer 13 by means of the projections 12 on said washer operating against the surface of the spiral and thereby driving said shuttle washer 13 which 5 relatively operates roller tubes. 16 is a piston or washer carried by spiral driving cam 14 operating within roller tube 9 to steady and carry said driving cam and act as a stop 10 to limit its withdrawal from said tube when contacting with shuttle washer 13.

17 is the bridge which is formed with retaining members 18 stamped and bent so as to carry shuttle washer 13 permitting 15 rotation thereof, but securing the position longitudinally thereof relatively with reference to said bridge. In bridge 17 is also operating opening 19 through which blade reverse cam spiral 20 operates.

21 is the blade holder. We have found that the blade holder can be cheaply and very successfully stamped when formed from sheet metal; and in doing this we provide a handle 22 formed to lay parallel with the 25 razor blade when in position to indicate its position within the stropping machine when a withdrawal of the same is desired. 23 and 24 are projections to register with the holes in the razor blade for positioning purposes.

30 Portions 25 and 26 are cylindrical formed operating surfaces, or guides, for operating within double slotted tube 27. 28 is a projection acting as a stop in the withdrawal of the blade holder to limit its movement outward, the same bringing up against the head 35 on the inside. In cylindrical portion 26 undercut 29 is made to facilitate the holding of the blade in withdrawal. Projection 30 is formed with a similar undercut.

40 Double slotted tube 27 permits the razor blade 31 carried by blade-holder 21 to project on both sides thereof through said slots, said slots being open to the end of said tube at one end which end revolves in head 4 as a bearing, and which head is provided with opening 32 to permit the withdrawal of the blade, the other end of said tube being secured to blade reverse cam spiral 20 and is operated thereby. Said reverse cam spiral 45 20 is journaled in a depression in end 3 of the casing and is provided with an exterior washer secured to said spiral to prevent relatively endwise displacement, but permitting rotation. Bridge 17 operates said spiral 20

by means of opening 19 when said bridge 55 is longitudinally displaced with reference to said spiral, this displacement being caused by the displacement of the spirals 14 in their reciprocation.

In the above description of the drawings, a two-faced spiral and a two-slotted roller tube have been described; three or more faces of the spiral have been used in conjunction with three or more slots in the roller tube. We do not limit ourselves to any number of faces of the operating spiral. Similar remarks apply to the blade reverse cam where two surfaces are shown, but three or more may be used, if desired. We have used three very successfully, and do not wish to 65 be limited to any number.

In this specification and claims, when we use the term "twisted" members, we mean thereby spiral members.

Having thus described our invention, what 75 we claim and desire to secure by Letters Patent is:

1. A razor stropper comprising a stropping roll, a tube forming a mounting shaft therefor, a spiral cam rod reciprocable to 80 rotate said roll, a shuttle washer having a perforation to surround the spiral cam rod and having inward projections to engage the grooves of the cam, the roller mounting tube also passing through said perforation 85 and slotted to permit said projections of said shuttle washer to pass therethrough and so that the tube may slide axially through said shuttle washer, but may also be rotated thereby, one of said slots extending to the end of 90 said tube to permit ready assembly by threading of the spiral cam rod and tube through said shuttle washer.

2. A razor stropper comprising, stropping rolls, mounted upon tubes, within which 95 telescope spiral cam rods shuttle washers having apertures with inward projections engaging the grooves of the spiral cam rods and also passing through slots in the projecting ends of the roller mounting tubes, 100 a bridge-plate having apertures registering with those of the shuttle washers and overhanging flanges which position and retain said shuttle-washers in contact with one side of bridge-plate.

GEORGE W. HOOS.
